UNITED STATES PATENT OFFICE.

CHARLES B. MOHR, OF NEW YORK, N. Y.

REVERSIBLE-SIGN STRUCTURE.

1,081,297.

Specification of Letters Patent.

Patented Dec. 16, 1913.

Application filed October 10, 1912. Serial No. 735,031.

To all whom it may concern:

Be it known that I, CHARLES B. MOHR, a citizen of the United States, residing at New York, in the county of New York and State 5 of New York, have invented new and useful Improvements in Reversible-Sign Structures, of which the following is a specification.

This invention relates to reversible sign 10 structures, and is especially adapted for use in connection with automobiles to display the license numbers under which the machine is operated.

Inasmuch as machines are often operated 15 under licenses granted from more than one State, it is the practice to display the license numbers of all the States in which the owner possesses licenses, and this display of numbers somewhat detracts from the finished 20 appearance which is desirable even at the rear of a machine.

It is one of the objects of my invention to provide a reversible sign structure whereby 25 more than one license number may be carried, while only one is displayed during travel in the State corresponding to one of the numbers.

It is well known that license numbers of 30 different States are not of uniform size and it is therefore one of the objects of my invention to provide a frame adjustment for compensating for various sized boards and also rotatable adjustment for supplementing the adjustment of the frames.

35 Minor objects will hereinafter appear as the invention is described in connection with the accompanying drawings, wherein the preferred embodiment of my invention is shown, and in which drawings:

40 Figure 1 is a front elevation of the device. Fig. 2 is a view partly in section and taken on the line 2-2 of Fig. 1, with the sign in a slightly changed position with respect to the position thereof shown in Fig. 1 and, 45 Fig. 3 is an enlarged detail view illustrating the spring locking means for the number plate.

Referring to the drawings, 1 designates a 50 bracket which is adapted to be suitably supported upon an automobile or other vehicle either from the frame, radiator or other device. The bracket in the instance shown, is provided with an arm 2, adapted to be secured to the frame of a vehicle by means of 55 bolts 3. Said bracket 1 is provided with side arms 4 one of which is deflected at 5

and terminates in a shank 6, from which a lamp may be removably supported. The arms 4 rise from a cross arm 4^a which is connected to and distanced from the arm 2 by 60 an arm 4^b. This distancing feature permits of the adjustment of the sign, to be herein-after referred to, without interference with the frame of the vehicle.

The sign holder of my device is generally 65 designated 7 and comprises holder sections designated 8. Each holder section is provided with a projection or bolt 9 adapted to extend through an opening in the arm 4, by means of which bolts or projections the 70 sections 8 are pivotally or swingingly mounted. Beyond the arms 4 the bolts 9 are provided with nuts 10. The holder sections 8 are provided with arms designated 11 in which are provided suitable elongated slots 75 12. On opposite sides of the holder members are secured signs or number plates 13 by means of screws or bolts 14, adapted to pass through the elongated slots 12. The elongated slot construction permits signs to 80 be accommodated in the device, which have their bolts or other attaching means arranged at different distances apart. If further adjustment is necessary the arms 8 can be moved inwardly to some extent, through 85 the loosening of the nuts 10.

Means is provided for securing the sign in its adjusted position and consists of a leaf spring designated 15 fastened as at 16 to one of the arms 4. Said spring carries a 90 pin or lug 17 which extends through an opening in the arm 4 as shown, and is adapted to engage slots or cavities 18 in the adjacent holder member 8.

The two signs 13 are different and usually 95 bear the numbers for different States of the United States.

In operation, when the number for one State is to be displayed, as when traveling through said State, the spring 15 is moved 100 outwardly so that the lug 17 disengages the slots 18, and the sign holder is adjusted to bring the proper sign to the desired position, thereupon the spring 15 is released and its pin 17 engages in one of the notches 13 105 and locks the device in said position. When it is desired to display the other sign, it is merely necessary to adjust the device as before, so as to bring said other sign to proper position and lock the same therein.

It is also to be understood that I have shown and described merely the preferred

form of my invention, and that in addition to the change set forth, other details of construction of the device may be varied within the spirit and scope of the appended claim.

Having thus described my said invention, what I claim and desire to secure by Letters Patent is:—

In a reversible sign structure, supporting arms in spaced relation with respect to each other and provided with aligned bearings, separate end sign-holding frames each having slotted portions for engagement with sign bodies and their attaching devices, a plurality of sign bodies mounted in said frames and having means extending through said slotted portions to anchor the sign bodies to said frames with the face of one sign

body exposed on one side of said frames and the face of another sign body exposed on the other side of said frames, each frame having a stud journaled in one of said bearings, and means for independently adjusting said studs longitudinally in said bearings to afford sign body attaching adjustment in addition to the adjustment afforded by said slotted portions, and means carried by one of said arms for locking the frames in a position to display either of the exposed signs, substantially as described.

CHARLES B. MOHR.
